US00D807170S

(12) **United States Design Patent** (10) Patent No.: **US D807,170 S**
(45) Date of Patent: ** Jan. 9, 2018

(54) **CONTAINER**

(71) Applicant: **WELLS ENTERPRISES, INC.**, Le Mars, IA (US)

(72) Inventors: **Scott L. Fisher**, Evansville, IN (US); **Jason Allen Rowe**, Santa Claus, IN (US)

(73) Assignee: **Wells Enterprises, Inc.**, Le Mars, IA (US)

(**) Term: **15 Years**

(21) Appl. No.: **29/534,424**

(22) Filed: **Jul. 28, 2015**

(51) LOC (11) Cl. **09-03**

(52) U.S. Cl.

USPC **D9/428**

(58) **Field of Classification Search**

USPC D7/538-545, 602, 608, 629; D9/396.1, D9/414, 420, 424-429, 432, 761; 206/501-509; 220/781, 791, 793, 220/811-813, 835, 839

CPC B65D 1/24; B65D 25/04; B65D 43/03; B65D 43/16

(74) Attorney, Agent, or Firm — Barnes & Thornburg LLP

(57) **CLAIM**

The ornamental design for a container, as shown and described.

DESCRIPTION

FIG. 1 is a top perspective view of a container, showing our new design;

FIG. 2 is a bottom perspective view thereof;

FIG. 3 is a front elevational view thereof;

FIG. 4 is a back elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken line portions show unclaimed subject matter only and form no part of the claimed design.

1 Claim, 4 Drawing Sheets
